UNITED STATES PATENT OFFICE.

JOHN H. McILVAINE, OF LAKE FOREST, ILLINOIS.

LIQUID-FUEL BURNER.

Application filed September 8, 1925. Serial No. 54,861.

This invention relates to the burning of liquid fuel in what is commonly known as oil burners for both domestic and commercial purposes.

5 The present invention has for its principal object the provision of a novel means for burning liquid fuel continuously at high, low and intermediate loads as distinguished from some types of burners designed to burn intermittently because of their inherent inability 10 to operate at a comparatively low load. The intermittent type of burner requires, therefore, either a pilot light or ignition means and more or less complicated control 15 devices incidental to the intermittent operation, which are unnecessary with my invention.

My invention also aims to secure more 20 complete and efficient combustion by reason of the improved method by which the oil is vaporized, and by which the oil vapor and the air are mixed in the proper proportions for combustion at the different loads.

25 Another purpose of my invention is to overcome certain difficulties inherent in prior oil burners such for example, as the formation of carbon, noise created especially at high loads, improper proportioning and 30 mixing of the air and oil at all loads, flickering out at low load, and blowing out at high load. In addition to overcoming these objections my improved burner produces a horizontally issuing flame at the higher 35 loads which is desirable especially in installations in heaters and furnaces, as will be described more fully hereinafter.

In furtherance of the foregoing general 40 objects my invention contemplates the provision of a combustion chamber or fire pot in a vertical position and the delivery of the oil and air downwardly into the combustion chamber from the top thereof, as distinguished from the conventional horizontal 45 combustion chamber having a lateral air and oil inlet. Furthermore, the combustion chamber is shaped to provide a small pocket or auxiliary combustion chamber in which the oil burns at all loads but which is primarily 50 designed for burning at the low load without flickering out and without the formation of carbon to any detrimental degree. The combustion chamber is further shaped to produce a peculiar and novel 55 method of vaporizing the oil and mixing the oil vapor and air so as to secure complete

combustion at all loads and to cause the flame to issue from the combustion chamber in a most advantageous manner, all of which will be explained more particularly hereinafter.

60 Other objects and attendant advantages will be appreciated by those skilled in this art as the invention becomes better understood by reference to the following description when considered in connection with the accompanying drawing, in which—

Fig. 1 is a vertical section through a furnace equipped with a liquid fuel burner embodying my invention;

70 Figs. 2, 3, and 4 are top, side and front views respectively, of the combustion chamber or fire pot; and

75 Figs. 5, 6, and 7 are diagrammatic views corresponding with Figs. 2, 3, and 4, respectively, illustrating combustion at a low load.

While my invention may be utilized in many different commercial and domestic installations it is primarily intended for domestic heating purposes where efficiency, 80

quietness, and a wide range of loads are important factors. In the present case I have, therefore, shown the combustion chamber installed in a furnace, this installation being the same as disclosed in my copending application Serial No. 45,448, filed July 23,

1925, which shows a complete apparatus for delivering air and oil in positively regulated proportions to the combustion chamber. In this example the fire pot designated generally by 8 is supported in an upright position on a base 9 which rests on the furnace grates 11 over which a layer of fire brick 12 is placed. Air is delivered to the fire pot

8 by any suitable means such, for example, as through a pipe 13 from a blower as explained in said copending application. The pipe 13 enters the heater or furnace through the fire door 14 and has a vertical end 15 which sets into the top inlet end 16 of the

fire pot. The oil supply is through a pipe 17 which preferably is disposed within the air delivery pipe as described in said copending application and has a vertical end 18 terminating in a sharp delivery point 19 from which the oil may drip in a steady

feed into the combustion chamber at an unusually low feed per hour.

The air and oil enter the combustion chamber through an inlet opening 21 in the top horizontal wall 22 of the fire pot, this opening being preferably rectangular in cross-

section as shown in Fig. 2 and spaced forwardly from a vertical back wall 23 and located contiguous to a vertical side wall 24 at right angles to said back wall. At the bottom of the fire pot at the juncture of the back and side walls 23 and 24 is formed a pocket designated generally by 25 which provides an auxiliary or low load combustion chamber. As shown in Fig. 2 the rear wall 10 26 of this pocket is coplanar with the vertical wall 23 and the opposite wall 27 is of semi-conical shape the curvature of which tends from a base plane 28 at the back wall 23 forwardly to the apex 29 on the side wall 15 24. The bottom of the combustion chamber is inclined from the lowest point 31, which is the lowest point in the pocket 25 directly beneath the side wall 24 as shown in Fig. 4, upwardly away from said pocket at a low, 20 gradual angle providing an inclined portion 32, the purpose of which will be described hereinafter. The side wall 33 opposite the wall 24 is curved in the form of a semi-section of a frustum of a cone extending 25 from the back wall as a base to the truncated end at the front or outlet end of the fire pot. This side wall 33 in addition to its curvature is at an acute angle with respect to the back wall 23 both in a horizontal plane 30 as shown in Fig. 2 so as to converge with the opposite side wall 24 and in a vertical plane as shown in Fig. 3 so as to converge with the top wall 22. This inclination of the side wall 33 causes it to merge into the front wall 35 34 which in turn follows the general curvature of said side wall 33 and merges into the opposite side wall 24. The outlet 35 through which the flame issues from the combustion chamber is circular and located at the front 40 of the fire pot tangential to both the top wall 22 and the side wall 24.

In Figs 5, 6 and 7 I have shown diagrammatically the operation at the low load, the light arrows A indicating the incoming air, 45 the heavy dotted lines B the dripping oil, the heavy arrows C the flame and the light arrows D the hot gases. It will be noted that the incoming air passing directly down along the side wall 24, impinges against the 50 inclined front wall 34 and bottom 32 and is deflected in part into the pocket 23 where it is caused to whirl or rotate by reason of the shape of said pocket from which it passes into the main combustion chamber in a 55 whirling mass which revolves about a horizontally disposed axis substantially parallel with the back wall as noted by the long heavy arrow in Figs 5 and 7. The remainder of said incoming air passes directly into 60 the main combustion chamber and is caused by the curved and inclined walls thereof to whirl as indicated by the arrows D about an axis indicated by the long light arrows in Figs. 5 and 6, it being noted that the whirling air, or mixture, issuing from the smaller

pocket emerges into the whirling air, or mixture, in the main part of the combustion chamber. The oil which drips slowly and steadily at the low load at the rate of about five per cent or less of the maximum oil feed 70 impinges on the bottom wall of the combustion chamber which needs to be pre-heated by any suitable means only when starting the burner. The means for preheating is also utilized for initially igniting the 75 fuel mixture. The oil dripping on the heated surface 32 is vaporized by contact with the heated surface and mixed with the whirling air in the small pocket so that the fuel burns intensely in this pocket and the flame 80 issues into the main combustion chamber as illustrated by the heavy arrows in Fig. 7. By reason of this construction, whereby the flame burns in a pocket protected from the main blast of air, it is possible to support 85 thorough combustion at a remarkably low oil feed per hour which I have termed the low load and which in practice is not intended for heating the furnace but rather for maintaining a constant flame and for 90 keeping the fire pot heated sufficiently to maintain continuous combustion and to enable the flame to be increased at will or under thermostatic control without the use of a pilot light or ignition means employed in 95 burners which operate intermittently. It will be noted more particularly that the oil drips onto the heated inclined bottom wall 32 and runs down this heated surface to the lowest point 31 which I have termed the 100 vaporizing point. The oil will be vaporized by contact with said heated surface and by action of the air and will be ignited by the flame. At the low load practically all of the oil vapor is carried into the small pocket or 105 auxiliary combustion chamber and is burned therein. At higher loads, however, the oil dripping onto the inclined bottom wall 32 forms a film thereon which is heated by contact therewith and vaporizes. By reason of 110 the inclination of the lower portion of the front wall 34 and the bottom wall 32 and especially the low angle of the latter the oil film spreads out at the higher loads over a considerable area so that there is contact 115 with the hot metal surface for a period sufficient to produce vaporization. Another advantage of the inclined bottom wall is that it always insures flow of oil into the low load pocket regardless of whether the fire pot is accurately leveled. At the higher loads the mixture splits into two parts, the smaller part entering the pocket 25 and burning intensely so as to maintain a comparatively high heat in the vicinity of the 120 vaporizing point, and the larger part following the curvature of the side wall 33 and burning in a whirling or rotating flame. It will be observed that this burning mixture is retarded or held back in the com- 125 130

bustion chamber by reason of the inclination and converging relation of the walls 33 and 34 with respect to the opposite walls so that a thorough admixture of the oil vapor and air is effected within the main combustion chamber. The flame burns intensely within said chamber and as the fuel and air increase at the higher loads the flame spreads out horizontally from the outlet opening 35 in a whirling cone finally extending at the full load a distance from the fire pot, approximately as shown by the arrows in Fig. 1.

It is believed that the foregoing conveys a clear understanding of the objects prefaced above and while I have illustrated but a single working embodiment it should be understood that changes might be made in adapting the fire pot to different installations without departing from the spirit and scope of the invention as expressed in the appended claims, in which—

I claim:

1. A fire pot for burning liquid fuel having a main combustion chamber said pot having means for delivering fuel and air into the same to a point at one side of said chamber, and a pocket in which the liquid fuel is adapted to burn at low load, the 30 pocket being alongside the main combustion chamber at the point of fuel and air delivery within the fire pot.

2. A fire pot for burning liquid fuel having a main combustion chamber, said pot having means for delivering fuel and air into the same to a point at one side of said chamber, and an auxiliary combustion chamber, alongside the main chamber at the point of fuel and air delivery within the fire 40 pot, a greater proportion of the fuel being caused to burn in the auxiliary combustion chamber at low load and at higher loads a greater proportion being caused to burn in the main combustion chamber.

3. A fire pot for burning liquid fuel having an opening in its top through which air and liquid fuel are adapted to be delivered downwardly, a bottom surface onto which said air and liquid fuel are adapted to impinge and which during operation is heated and adapted for vaporizing the liquid fuel, the fire pot being shaped to provide a main and an auxiliary combustion chamber at opposite sides of said surface shaped so that at low load a greater proportion of the mixture passes into and is burned in the auxiliary combustion chamber and the products of combustion pass therefrom into the main combustion chamber and so that as the load increases a proportionately greater amount of the mixture passes into the main combustion chamber for burning therein, the main combustion chamber having an outlet opening through which the flame or products of combustion issue.

4. A fire pot for burning liquid fuel having a common air and liquid fuel inlet opening in its top, a main combustion chamber having a side outlet opening from which the flame or products of combustion issue, and a pocket off the main combustion chamber providing an auxiliary combustion chamber for low load combustion, from which auxiliary combustion chamber the flame or products of combustion issue into the main combustion chamber and thence through said outlet opening.

5. A fire pot for burning liquid fuel having a main combustion chamber and an auxiliary and smaller combustion chamber, in the latter of which liquid fuel is adapted to burn at low loads, said combustion chambers being disposed side by side, and means for delivering air and liquid fuel into said fire pot between the two chambers, combustion being caused to take place primarily in the auxiliary combustion chamber at low load and the flame or products of combustion issuing therefrom into the main combustion chamber and as the load increases the flame being crowded out of the auxiliary chamber and burning to a proportionately greater extent in the main combustion chamber.

6. An upright fire pot having a vertical back and a side wall in substantially right angular relation, a substantially horizontal top wall having an inlet opening near the juncture of said back and side walls, a low load pocket formed at the juncture of said back and side walls at the bottom thereof, the bottom wall being inclined upwardly away from the back wall, the side wall opposite from said vertical side wall being curved in a vertical plane and inclined forwardly from the back wall so as to converge with relation to said opposite side wall, and the fire pot having a circular outlet opening at its front substantially tangential to the top wall and the vertical side wall.

7. An upright fire pot having a vertical back and a side wall in substantially right angular relation, a substantially horizontal top wall having an inlet opening near the juncture of said back and side walls, a low load pocket formed at the juncture of said back and side walls at the bottom thereof, the bottom wall being inclined upwardly away from the back wall, the side wall opposite from said vertical side wall being curved in a vertical plane and inclined forwardly from the back wall so as to converge with relation to said opposite side wall, the fire pot having a circular outlet opening at its front substantially tangential to the top wall and the vertical side wall, said inlet opening being rectangular in cross-section and spaced forwardly from the back wall and contiguous to said vertical side wall, and the bottom wall beneath said opening being inclined downwardly with its

lowest point contiguous to the lowest point in the low load pocket to provide a vaporizing surface from which oil vapor is adapted to enter said pocket at low load but from which an increasingly greater proportion of oil vapor is adapted to be carried into the main combustion chamber as the load increases.

8. An upright fire pot having a vertical back and a side wall in substantially right angular relation, a substantially horizontal top wall having an inlet opening near the juncture of said back and side walls, a low load pocket formed at the juncture of said back and side walls at the bottom thereof, the bottom wall being inclined upwardly away from the back wall, the side wall opposite from said vertical side wall being curved in a vertical plane and inclined forwardly from the back wall so as to converge with relation to said opposite side wall, the fire pot having a circular outlet opening at its front substantially tangential to the top wall and the vertical side wall, said low load pocket having a wall substantially semi-circular in a vertical plane opposite from said curved side wall and decreasing in depth from the back wall at progressive points forwardly to a point of intersection with the inclined bottom wall and the vertical side wall.

9. A fire pot for burning liquid fuel having a vertical back wall, a vertical side wall at right angles to the back wall, an opposed side wall at an acute angle to the back wall and curved in a vertical plane, said opposed side wall merging at its top into a horizontal top wall and at its bottom into a bottom wall which inclines downwardly toward the back wall, the chamber having an inlet opening in its top wall and an outlet opening intermediate the top and bottom walls at the side opposite from the back wall.

10. A fire pot as set forth in claim 9, in which the inlet opening is located in the top wall at the juncture of the back wall and the first-mentioned side wall.

11. A fire pot as set forth in claim 9, including a low load pocket in the first-mentioned side wall at the bottom thereof.

12. A fire pot as set forth in claim 9, in which the inlet opening is located in the top wall at the juncture of the back wall and the first-mentioned side wall, and including a low load pocket in the said side wall at the bottom thereof adjacent to the back wall.

13. A fire pot for burning liquid fuel having a main combustion chamber one side of which is in the form of a semi-section of a cone frustum and the other side of which has a semi-conical pocket providing a low load combustion chamber.

14. A fire pot for burning liquid fuel having a main combustion chamber and an aux-

iliary combustion chamber disposed side by side and having fuel and air delivered just between the same, the sides of both chambers being curved to cause the fuel mixture to move and burn in a whirl, the curvature of the auxiliary chamber being abrupt and that of the main chamber a gradual sweeping curvature, the fuel mixture being arranged to burn in a whirling mass in the auxiliary chamber at a comparatively low load.

15. An upright fire pot having a vertical back and a side wall in substantially right angular relation, a substantially horizontal top wall having an inlet opening therein, a low load pocket formed at the juncture of said back and side walls at the bottom thereof, the bottom wall being inclined upwardly away from the back wall, the side wall opposite from said vertical side wall being curved in a vertical plane and inclined forwardly from the back wall so as to converge with relation to said opposite side wall, and the fire pot having a front flame opening.

16. An upright fire pot having a vertical back and a side wall in substantially right angular relation, a substantially horizontal top wall having an inlet opening therein, a low load pocket formed at the juncture of said back and side walls at the bottom thereof, the bottom wall being inclined upwardly away from the back wall, the side wall opposite from said vertical side wall being curved in a vertical plane and inclined forwardly from the back wall so as to converge with relation to said opposite side wall, the fire pot having a front flame opening, said inlet opening being spaced forwardly from the back wall and contiguous to said vertical side wall, and the bottom wall beneath said opening being inclined downwardly with its lowest point contiguous to the lowest point in the low load pocket to provide a vaporizing surface from which oil vapor is adapted to enter said pocket at low load but from which an increasingly greater proportion of oil vapor is adapted to be carried into the main combustion chamber as the load increases.

17. An upright fire pot having a vertical back and a side wall in substantially right angular relation, a substantially horizontal top wall having an inlet opening therein, a low load pocket formed at the juncture of said back and side walls at the bottom thereof, the bottom wall being inclined upwardly away from the back wall, the side wall opposite from said vertical side wall being curved in a vertical plane and inclined forwardly from the back wall so as to converge with relation to said opposite side wall, the fire pot having a front flame opening, said low load pocket having a wall substan-

tially semi-circular in a vertical plane opposite from said curved side wall but on a smaller radius.

18. A fire pot of the character described, 5 having a vertical back wall and a side wall in substantially right angular relation, a top wall having a fuel and air inlet opening therein, a semi-conical main combustion chamber having the back wall as a base and 10 formed on one side of the side wall in direct communication with the aforesaid inlet opening, the curvature of the walls of said chamber being of relatively ample radius, and an auxiliary combustion chamber provided on 15 the other side of the side wall having curved walls on a relatively small radius, said chamber being in open communication with the main combustion chamber, and hence indirectly in communication with the aforesaid 20 inlet opening by way of the main combustion chamber.
19. A fire pot as set forth in claim 18, wherein the auxiliary combustion chamber is likewise of semi-conical form with the 25 base thereof at the back wall.
20. A fire pot for burning liquid fuel comprising a main combustion chamber, and an auxiliary combustion chamber formed as a lateral extension of the main combustion 30 chamber, the bottom walls of both of said chambers being inclined toward a common low point, and said pot having means for delivering fuel and air into the same in the vicinity of said low point.
21. A fire pot for burning liquid fuel comprising a main combustion chamber, and an auxiliary combustion chamber formed as a lateral extension of the main combustion 35 chamber, the bottom walls of said chambers being inclined toward a common low point which marks the separation of the auxiliary 40 chamber from the main chamber, and said
- pot having means for delivering fuel and air into the same between the two chambers in the vicinity of said low point. 45
22. A fire pot having a vertical back wall and a side wall in substantially right angular relation, a main combustion chamber formed on one side of said side wall, and an auxiliary combustion chamber formed on the 50 other side of said side wall opening off the lower end of the main combustion chamber, the bottom walls of both chambers being inclined toward a common low point at the lower end of said side wall, and said fire pot 55 having means for delivering liquid fuel and air into said main combustion chamber along the side wall to the vicinity of the low point.
23. A liquid fuel burner fire pot having a main chamber and an ante-chamber opening 60 off the same, the said pot having inlet and outlet openings common to the two chambers for the intake of fuel and air and the outlet of the products of combustion, the main chamber being formed of the proper size and 65 proportions for high load operation, and the ante-chamber being formed of the proper size and proportions for low load operation, the pot having means for delivering fuel and air therein between the two chambers and at 70 the entrance into the ante-chamber so that the mixture burns in the ante-chamber practically entirely at low load and is thereby insured against being extinguished, and burns to a greater and greater extent in the main 75 chamber as the flame is crowded out of the ante-chamber in the increased feeding of fuel and air, whereby the low load flame serves as a nucleus in the building up to the high load flame. 80

In witness of the foregoing I affix my signature.

JOHN H. McILVAINE.
